CLAIM

The ornamental design for a ceiling fan, as shown and described.

DESCRIPTION

FIG. 1 is a top perspective view of a ceiling fan, showing my new design;

FIG. 2 is a bottom perspective view of the ceiling fan of FIG. 1;

FIG. 3 is a top view of the ceiling fan of FIG. 1;

FIG. 4 is a bottom view of the ceiling fan of FIG. 1;

FIG. 5 is a left side view of the ceiling fan of FIG. 1;

FIG. 6 is a rear view of the ceiling fan of FIG. 1;

FIG. 7 is a right side view of the ceiling of FIG. 1; and,

FIG. 8 is a front view of the ceiling fan of FIG. 1.

The blade portion of the ceiling fan is shown with a symbolic break in its length. The appearance of any portion of the article between the break lines forms no part of the claimed design.

1 Claim, 8 Drawing Sheets
